Attorney

UNITED STATES PATENT OFFICE.

ARTHUR JAMES LISTER, OF BRADFORD, ENGLAND.

SOCK-SUSPENDER.

1,244,218.

Specification of Letters Patent. Patented Oct. 23, 1917.

Application filed August 14, 1917. Serial No. 186,185.

To all whom it may concern:

Be it known that I, ARTHUR JAMES LISTER, a subject of the King of England, and residing at Bradford, in the county of York, England, have invented Improvements in Sock-Suspenders, of which the following is a specification.

This invention has reference to sock or stocking suspenders of the type in which a 10 garter is employed which fits around the leg, and carries a gripping device proper, which engages the edge or body of the sock or stocking and supports it.

The gripping suspending device proper 15 is secured to the garter through an elastic or expandible ring, and this ring is held up by loops on the end of the garter, one end of which is secured to the garter body by a press button clip or the like, and the 20 other to the other end of the garter by a buckle or the like.

The fastening or clip device proper for securing and holding the sock is of the type having a stud on a plate which passes 25 through a link; and in the fastening act, these two parts are put on the opposite side of the sock, and they are pressed together, and the material of the sock is pressed between the stud and the link, so that it will 30 be gripped between these parts.

This gripping device is carried from the elastic or expandible ring by a band, having a press button clip or like fastener on its ends.

35 With regard to the features claimed as novel in respect of the herein described invention, these are set out in the clauses of the statement of claim concluding the specification.

40 The invention is illustrated in the annexed drawing, which shows a suspender having the characteristics above specified; and it will be further described with the aid of this drawing.

45 Referring to the drawing, *a* is the garter or leg piece; *e* is the elastic or expandible ring—which is preferably of rubber; and *i* is the sock or stocking gripping device.

Of the leg piece or garter *a*, *b* represents 50 a press button clip or fastener device, part of which—say the stud—on the end of it, being normally engaged with the socket device on another part of the garter. This press button clip will be similar to the 55 common press button clips used on gloves and other articles of apparel. On the other

end of the garter a buckle *c* is fixed, which may be adjusted to and fastened in any of the holes provided in the garter.

In securing the ring *e* to the garter *a*, 60 the end of the garter is passed through it, and then through the buckle *c*; and then the other end is passed through the ring, and the press button clip or fastener *b* is fastened. The ring *e* is thus secured to the 65 garter.

The gripping device *i* is secured to the ring *e* by the band *f*, which has on it a press button clip fastener *h*, similar to *b*; so that by passing this band through the 70 ring *e*, and the link *k* of the gripping device *i* (which is of well-known form), this device is connected to the ring.

The device *i* consists of the link *k*, flap *l*, 75 and stud *m* on this flap. The link is of a form commonly used in this type of gripping device, and the projecting stud *m*, when the device is closed, passes down into the narrow part of the link, the edge or material of the sock or stocking being first 80 introduced over the stud.

It will be seen that resiliency in the suspender is afforded by the elastic or expandible ring *e*, which as stated, is preferably of rubber; and this part, which is the part 85 more likely to require renewal, can be renewed and a fresh one secured to the garter and strap *f* by the readily attachable and detachable means described.

While the fastening devices described for 90 the different parts, can be advantageously employed, yet equivalent fasteners or fastening devices, such as buttons, studs, hooks or like fasteners, may be employed instead of them.

95 What is claimed is:—

1. A suspender for socks or stockings comprising in combination a practically inelastic garter or band *a* adapted to fit around the leg; a gripping device *i* for gripping the sock or stocking, and an elastic or expandible ring *e* detachably secured by the 100 ends of the garter *a*, and a band *f* by the lower end of which the aforesaid gripping device *i* is suspended; substantially as described.

2. A suspender for socks or stockings comprising in combination a garter or band *a* having a press button fastener *b* connecting one end to the body, and a buckle fastener *c* for fastening the other end to the body; an elastic ring *e* passed through the 110

looped ends of the band *a*, a looped band *f* surrounding the ring *e* having its ends secured by a fastener *h*, and a gripping device *i* secured in the looped band *f*, and comprising a link *k*, and a plate *l* carrying the button *m*; substantially as herein set forth.

In testimony whereof I have signed my name to this specification in the presence of two subscribing witnesses.

ARTHUR JAMES LISTER.
